UNITED STATES PATENT OFFICE.

CALVIN C. WILLIAMS, OF PHILADELPHIA, PENNSYLVANIA, ASSIGNOR TO VICTOR
VACUUM CLEANING COMPANY, OF PHILADELPHIA, PENNSYLVANIA.

VACUUM-CLEANER PUMP.

1,072,547.

Specification of Letters Patent.

Patented Sept. 9, 1913.

Application filed April 30, 1912. Serial No. 694,110.

To all whom it may concern:

Be it known that I, CALVIN C. WILLIAMS, citizen of the United States, residing at Philadelphia, in the county of Philadelphia and State of Pennsylvania, have invented 5 certain new and useful Improvements in Vacuum-Cleaner Pumps, of which the following is a specification.

My invention relates to vacuum cleaners, 10 and particularly to that class of cleaners adapted to be operated by hand, and wherein a vacuum pump is combined with a dust collecting chamber, the pump being operated by the movement of the vacuum cleaner.

15 The primary object of my invention is to provide a cleaner with a positive vacuum-creating pump of such character that it will not readily get out of order, and in which wear will be reduced to a minimum.

20 A further object is to provide a cleaner of this character which is extremely compact in form for the reason that the pump is contained within and forms part of the traction member or roller and is actuated by cams 25 carried by and rotatable with the roller.

A further object is to provide means whereby a dust-proof joint may be formed 30 between the casing of the collecting chamber and the pump, this joint being so arranged that all wear may be taken up.

35 A further object is to provide a vacuum cleaner of this character wherein the point of application of the handle may be changed so that more or less force may be applied to the head forming the end of the dust collecting casing and thus the head either be allowed to rest of its own weight upon the surface being cleaned or be positively forced 40 into contact with this surface.

45 Other objects will appear in the course of the following description.

My invention is illustrated in the accompanying drawings wherein:

Figure 1 is a perspective view of my improved cleaner. Fig. 2 is a longitudinal vertical section on the line 2-2 of Fig. 3. Fig. 3 is a horizontal section on the line 3-3 of Fig. 2. Fig. 4 is a longitudinal section through the cams and roller. Fig. 5 is 50 a perspective view of the two cams separated from each other and from the roller proper. Fig. 6 is a perspective detail view of the head forming the end wall.

Corresponding and like parts are referred to in the following description and indicated 55 in all the views of the accompanying drawings by the same reference characters.

Referring to the drawings, 2 designates the dust collecting chamber which preferably has the form of a cylindrical casing 60 open at one end, this open end being formed with inwardly projecting flanges 3 disposed inward of the extremity of the casing and forming a seat for a gasket or packing ring 4. Insertible into the seat thus formed and 65 against the packing ring 4 is a cleaner head 5 shown in detail in Fig. 6. This cleaner head has a circular portion designated 6 which is circular so as to fit within the open 70 end of the dust-collecting casing 2 and which is formed with the downwardly extending duct 7, this duct flaring at its lower end and being provided at its extremity with the outwardly projecting flanges 8, these 75 flanges being designed to rest upon the floor or carpet and to make an air-tight engagement with the floor and carpet as the cleaner is moved over the same. The middle portion of the head 5 is outwardly bulged as at 9. The cleaner head is held in place on the 80 end of the casing 2 by means of a clamp bar 10 which is bowed and formed at its ends with the inwardly turned terminal portions 11 designed to engage over lugs 12 formed of opposite points in the diameter of the 85 casing 2. This bowed clamp arches over the end of the cleaner head and passing through the middle of the clamp is a clamp screw 13 which engages against the middle 90 of the head and forces it inward against the gasket 4.

Held between the gasket 4 and the flange 3 is the margin of a dust-collecting bag 14 which may be made of any suitable material of fine enough mesh to catch any dust which 95 may be drawn into the collecting chamber or casing. Formed with the collecting chamber or casing and at the rear end thereof are the rearwardly extending laterally opening ducts 15. These ducts flare toward 100 their outer ends, that is, are inwardly tapered.

The vacuum-creating mechanism includes a pump cylinder designated generally 16 and comprising the barrel 17 and the end 105 plates 18. The barrel 17 is preferably

formed at its ends with the outwardly turned flanges 19 to which the end plates are attached by means of screws or in any other suitable manner. Disposed within the barrel are the double pistons 20 connected by means of a central stem 21.

Each of the end plates 18 is formed at its center with an opening 22 and the walls of this opening project outward as at 23. Connecting the opening 22 with the ports 15 are the ducts 24. These ducts as illustrated in Fig. 3 have inwardly turned extremities 25 which project into the openings 22 and engage with the walls 23. The opposite ends 15 of the ducts, that is, the forward ends thereof have inwardly turned nozzles 26 which are tapered and fit snugly in the flaring ends of the ducts 15. The forward ends of the ducts 24 are provided with the forwardly 20 projecting lugs 27 and these lugs are held in engagement with the rear end of the dust collecting chamber 2 by means of screws 28, these screws passing through the lugs 27 and into thickened portions of the wall of the dust collector 2. By tightening up on these screws, the terminal ends 26 of the ducts may be forced into dust-proof engagement with the ducts 15 and all wear 25 may be taken up. At the same time by re- 30 moving these screws 28, the ducts 24 may be readily disconnected both from the pump and the dust-collecting cylinder and the machine disassembled.

For the purpose of operating the pump, 35 I provide a traction member in the form of a roller adapted to rest upon the floor and within which the pump is inclosed. This roller consists primarily of an annulus designated 29 and of oppositely disposed cams 40 30 and 31 which are complementary to each other. These cams 30 and 31 are of skeleton formation so as to make them as light as possible, and are provided with lugs 32. The annulus 29 is also provided with inwardly extending lugs 33 engaging with the lugs 32. Screws 34 pass through the lugs and hold the annulus in proper relation to the cams. There are two of these cam members each approximately cylindrical in cross 45 section but having cam faces 35 on their inner ends. As illustrated these cam faces have the form of a sine-curve and are spaced apart just sufficient to permit the passage of a roller as will be later stated. Each of 50 the cam members 30 and 31 is provided on its outer end with the transversely extending bars 36 carrying an annular hub 37. This annular hub is just large enough to fit around the outwardly projecting walls 23 55 of the openings 22 as shown in Fig. 3 so that these walls 23 form bearings upon which the hubs 37 rotate. It will be of course understood that any sort of antifriction devices might be disposed between the 60 hub 37 and the annular wall 23 if desired.

Passing transversely through the spindle 21 which connects the pistons 20 is a spindle 38, which spindle is pinned or otherwise connected to the spindle 21, and the ends of the spindle 38 project out through longitudinal slots 39 formed in opposite portions of the barrel 17 as illustrated in Fig. 3.

Mounted upon the ends of the spindle 38 are the rollers 40, which rollers are held in place in any suitable manner as for instance by the pins 41. These rollers 40 bear against the cam faces 35, and it will be obvious that as the cams 30 and 31 rotate with the annulus 29, the cams will act to reciprocate the rollers 40, the spindle 38 and the pistons 20.

It is of course necessary to provide valves for controlling the inlet of air and the discharge of air from the pump cylinder, and to this end I provide inlet valves designated 41 which are seated in a valve seat formed in the ends 18 of the pump cylinder, these valves being held in place each by means of a spring 42 attached to the end 18 by means of a screw or other suitable device 43. It will be seen that when the adjacent piston moves away from the valve 41, the valve will open and the air will be drawn into the pump cylinder from the interior of the chamber or casing 2. An exhaust valve opening is also provided in each end wall 18, this opening being designated 44 and having a valve seat formed on the exterior of the end plate. Disposed in this valve seat is a valve 45 held closed by means of a spring 46. The spring 42 and the spring 46 are of similar construction, that is, each is coiled at one end so as to bear against the face of the valve. The spring 46 is attached to the outer ends of the wall 18 by means of a screw 47 or in any other suitable manner. It will be seen that when the piston approaches the valve 45, this valve will open and air contained within the cylinder will be forced out.

While I may provide any suitable handle 110 whereby this device may be operated, I have illustrated the handle 48 which has a bifurcated or forked lower end, the legs 49 of which are yieldable and formed at their extremities with inwardly turned terminal 115 portions 50, these terminal portions engaging in sockets 51 formed in the outer faces of the ducts 24, the ducts being thickened at this point for the purpose. Preferably there are a plurality of these sockets 51 and 120 I have shown three of such sockets. This permits the handle to be shifted farther forward or farther back so as to change the leverage exerted upon the dust-collecting casing 2 and therefore upon the head 5 by 125 means of the handle. Thus when the handle is disposed in the rearmost socket 51 but little force will be exerted upon the vacuum head and the head will rest upon the floor by its own weight. Where, however, it is 130

necessary that considerable force should be exerted, then the fork of the handle is shifted into the forwardmost socket.

The operation of my invention will be obvious from what has gone before.

With the parts assembled, the cleaner is intended to be pushed over the carpet or other surface to be cleaned, the mouth of the vacuum head being forced into contact with the surface. As the device is pushed over the floor, the roller will rotate with the cams 30 and 31, and the rotation of these cams will cause a reciprocation of the rollers 40, the spindle 38, the spindle 21 and the pistons 20. While one piston is drawing in air from the dust-collecting casing, the other piston is expelling air through the outlet opening. There is thus a continuous suction which I have found in practice will create a constant vacuum in the casing or chamber 2. I have found in practice that this construction is extremely effective and that it will pick up the finest particles of dust as well as relatively coarse particles.

It will be seen that the device is very substantially built and that no leather or other flexible material is used, and that no bellows is used, the leather of which is liable to wear out under action, or to become so cracked or split as to prevent a vacuum being formed. Furthermore, it will be seen that the parts may be readily disassembled to permit the pump pistons to be repacked if necessary, or the parts to be oiled or cleaned.

Again it may be pointed out that the connection between the cams and the pistons is extremely direct and positive, and that the parts may be made therefore relatively heavy, thus eliminating any danger of the parts bending under strain.

What I claim is:

1. A device of the character described including an annular traction member, a double acting pump disposed within the traction member and including a barrel extending longitudinally of the traction member and having openings at its ends coinciding with the axis of the traction member, a reciprocating piston within the barrel, means actuated by the traction member for reciprocating said piston parallel to the axis of the barrel and traction member, and a chamber operatively connected through the axis of the traction member with both ends of the pump barrel.

2. A device of the character described including in its organization an annular traction member, a double acting pump disposed within the traction member and extending transversely, and means actuated by the traction member for actuating said pump.

3. A device of the character described including in its organization an annular traction member, oppositely disposed cams car-

ried by and disposed within the traction member, and a double acting pump having opposed pistons and a barrel disposed transversely of and within the said cams, and a member operatively engaging said pistons and said cams to reciprocate the former upon a rotation of the latter.

4. A device of the character described including in its organization an annular traction member, oppositely disposed cams carried by the traction member and having cam faces spaced from each other, a pump barrel disposed within the cams and having an inlet and an outlet opening in each of its end walls, valves controlling the passage of fluid through said openings, connections extending from the inlet openings of the pump to the interior of the chamber, a double piston within the pump connected by a spindle, a transverse spindle engaging the first named spindle, the extremities of said last named spindle being engaged by the cam faces of the cams.

5. A device of the character described including in its organization a chamber carried thereby, a traction member, a pump including a pump barrel mounted within the traction member extending transversely of the said chamber and rearward of the same, ducts extending rearward from the said chamber and having tubular bearings entering the ends of the pump barrel whereby the chamber is pivotally connected to the pump barrel, and means operatively connected to the traction member for actuating said pump.

6. A device of the character described including in its organization a chamber having outwardly opening ducts having flaring walls, a traction member, a double acting pump mounted within the traction member and including a pump cylinder having openings at its opposite ends, means operatively connecting the pump with the traction member to actuate the former from the latter, tubular connections, each having a portion at one end projecting into the opening of the pump cylinder and forming a bearing for the same, the opposite end of each connection having a tapered portion projecting inward into the opening of the adjacent duct at the rear end of the chamber, and means of adjusting the forward end of each connection into engagement with the corresponding duct of the chamber.

7. A device of the character described including in its organization a chamber having laterally opening flaring ducts at its rear end, a traction member, a pump barrel mounted within the traction member, double pistons spaced from each other and disposed within the barrel, means operatively connected to the traction member for reciprocating said pistons, the end walls of the pump cylinder having centrally dis-

- posed inlet openings formed with outstanding walls, said end walls also being formed with outlet openings, inlet and outlet valves controlling said inlet and outlet openings, 5 tubular connections disposed one at each end of the pump barrel and having inwardly turned rearward extremities projecting into the centrally disposed openings of the barrel and forming bearings therefor, the forward ends of said connections having inwardly turned tapered extremities engaging with the ducts projecting from the chamber and also provided with lugs extending parallel to the rear end of the chamber, and adjusting screws passing through 10 said lugs and into the chamber.
8. A device of the character described including in its organization a chamber, a traction member having the form of an annulus and disposed behind the chamber, oppositely disposed spaced cam members having adjacent cam faces and operatively 15
- 20

nected to said annular traction member, a pump cylinder disposed concentrically to the cams and within the same, said cylinder being longitudinally slotted, end walls closing the ends of the cylinder and each having an outlet opening and a centrally disposed inlet opening having outstanding walls, said cams each having radial arms at 25 one end and a hub surrounding the outstanding wall of the adjacent end of the cylinder and rotatable thereon, and tubular connections, each engaging at one end the outstanding wall of the adjacent cylinder head and at the other end having operative engagement with the adjacent end of the chamber.

In testimony whereof I affix my signature in presence of two witnesses.
